ELECTRONIC WINDOW

Chester A. Johnson, Merrick, N.Y.

Application November 30, 1955, Serial No. 550,026

3 Claims. (Cl. 160—11)

This invention relates to windows for both domestic and commercial use and particularly windows in which operating parts thereof are adapted to be actuated by a flash of light, such as lightning or the flash of an atomic bomb for automatically closing a window; and in particular a circular sash rotatably mounted in a conventional window opening with a glass panel positioned on one side of the center of the circular sash and a blast screen in the other side or with the sash divided into sections of 120 degrees with a glass panel in one section, a blast shield in another section and a wire screen in the third section whereby with the window sash installed in a window frame and operated by a motor through electrical controls the motor may be actuated by a button to bring the desired portion of the circular sash in registering relation with openings through the window frame and whereas a sudden flash of light influences responsive elements of the window to actuate the motor to bring a blast shield or the like in position to completely close the window opening.

The purpose of this invention is to provide an automatically operated window in which the wear resulting from raising and lowering the sash is eliminated and in which the window is adapted to operate indefinitely.

Various types of motor controls have been provided for operating sash of double hung and casement windows, however, due to the necessity of sealing edges of windows and the difficulties encountered in endeavoring to seal areas between sliding elements it has been difficult to provide a completely power actuated window in which the window is sealed and in which continued operation of the window or sash thereof is assured.

With this thought in mind this invention contemplates mounting the window elements in a wheel and rotatably mounting the wheel in a window frame with all parts of the window opening sealed except an area positioned to register with a section of the wheel, and with means for rotating the wheel with the rotating means provided with manual and automatic controls.

The object of this invention is, therefore, to provide an improved electrically operated window in which an opening through the window may be closed with glass, a wire screen, or a blast shield, or the like by pressing a button to complete a circuit to a motor or other operating means.

Another object of the invention is to provide a rotatable window sash that provides a window opening of maximum size.

Another important object of the invention is to provide an electrically operated window that is adapted to be installed in window frames now in use.

A further object of the invention is to provide a safety window in which the window is adapted to be actuated by a flash of light, such as of an atom bomb to seal the window with a blastproof screen or shield.

A still further object of the invention is to provide an improved electrically operated window in which the

2

window is of a relatively simple and economical construction.

With these and other objects and advantages in view the invention embodies a wheel rotatably mounted in a window opening in which the wheel is provided with segments for sealing the window opening, or for positioning a glass panel in the window opening, or in which a wire screen may also be positioned in the window opening, and suitable controls for operating the window so that the window may be automatically actuated by a blast of light or operated by a switch button or controls positioned at remote points.

Other features and advantages of the invention will appear from the following description taken in connection with the drawings, wherein:

Figure 1 is an elevational view of the improved electronic window looking toward the inside of the window frame.

Figure 2 is a longitudinal section through the window frame showing the wheel forming a window sash with a motor for rotating the wheel and also showing one of the cleaning rollers for cleaning the surfaces of the wheel or sash.

Figure 3 is a front elevational view looking toward the outside of the window.

Figure 4 is a vertical section through the improved window taken on line 4—4 of Fig. 1 with the parts shown on an enlarged scale.

Figure 5 is a cross section through a portion of the window also with the parts shown on an enlarged scale showing the mounting and operating elements of the motor by which the wheel forming the window sash is rotated.

Figure 6 is a cross section through a portion of the window illustrating a solenoid actuated lock for locking the wheel forming the sash with glass, wire screen or a blast shield positioned in registering relation with the window opening.

Figure 7 is a cross section through the hub of the wheel, said section being taken through the portion of the wheel in which glass panels are positioned, the parts being shown on an enlarged scale and parts being broken away.

Figure 8 is a section similar to that shown in Fig. 7, the section being taken through the portion of the wheel in which the blast shield is positioned, parts of the wheel also being broken away.

Figure 9 is a section also similar to that shown in Fig. 7, the section being taken through the portion of the wheel in which the wire screen is positioned.

Figure 10 is a cross section through one side of the wheel of the window illustrating the arrangement, mounting, and operating means of cleaning brushes, the parts also being shown on an enlarged scale and parts being broken away.

Figure 11 is an elevational view of the brush operating elements being taken on line 11—11 of Fig. 10.

Figure 12 is a diagrammatic view illustrating a typical wiring circuit for supplying current to the motor showing a button actuated switch and also a flash responsive element for closing the circuit to the motor.

Figure 13 is a longitudinal section through the wheel forming the sash, similar to that shown in Fig. 2 illustrating a modification wherein the wheel is divided into two sections with a glass panel in one section and a blast or atomic shield in the other.

Referring now to the drawings wherein like reference characters denote corresponding parts the improved rotary window sash of this invention includes a wheel having a hub 10, a rim 11 with transversely disposed corrugations or teeth 12 on the peripheral surface, a pinion 13 having teeth meshing with the teeth 12 of

the wheel, a motor 14 operatively connected to the pinion 13 with a beveled pinion 15 positioned on a shaft 16 extended from the motor and a beveled gear 17 on a shaft 18 on which the pinion 13 is mounted, a locking pin 19 adapted to be positioned in openings 20 of the rim 11 of the wheel, cleaning brushes 21 and 22 rotated by the teeth 12 on the perimeter of the wheel through a pinion 23 held by an idler gear 24, beveled gears 25 and 26 on a shaft 27 and beveled pinions 28 and 29 meshing with the gears 25 and 26, respectively and connected to cores 30 and 31 of the brushes and, in the design illustrated in Fig. 2 the wheel is provided with arms 32, 33, and 34 dividing the wheel or sash into segmental openings 35, 36 and 37.

The hub 10 of the wheel is rotatably mounted by 15 roller bearings 37 on a flanged bushing 38 positioned on a shaft 39 and, as illustrated in Fig. 4 one end of the shaft is secured in a bearing 40 secured by a bolt 41 in a rear wall 42 of a housing and the opposite end is secured in a bearing 43 of a rail 44 extended across the intermediate part of the housing. The extended end of the shaft is also positioned in an opening in the lower edge of a front panel 45 providing a closure for the upper part of the housing and in which an opening 47, adapted to register with one of the segmental openings of the wheel, is provided. A spacing element 48 is also provided on the shaft 39 being positioned between the bearing 40 and a plate 49 on one end of the hub 10. A similar plate, as indicated by the numeral 50, is provided on the opposite end of the hub. The rear wall 42 of the housing is also provided with an opening 50 that is positioned in registering relation with the opening 47 in the opposite side.

In the design shown the housing is secured in an opening 51 of a wall 52 with fastening elements such as the screws 53 and the wall may be provided with an outer facing 54 to which the housing is secured with bolts 55 and an inner facing 56.

The inner portion of the housing is also provided with doors 57 and 58 that are secured in the housing with hinges 59 and 60, respectively and the doors are provided with knobs 61 by which the doors are adapted to be opened to provide access to the cleaning rollers 21 and 22 and also to the wheel and other mounting elements thereof.

In the design shown in Figs. 1, 2 and 4 the upper segment 35 of the wheel is provided with glass panels 62 and 63 which, as illustrated in Fig. 7, are mounted in grooves 64 and 65 of a channel-shaped member 66, the member 66 having a center rib 67 that is positioned between the panels. The member 66 extends on the inner surface of the rim 11 and also on the sides of the arms 32 and 33, and the grooves and also the rib 67 extend into the hub also as shown in Fig. 7.

In the section of the wheel in which the opening 37 is positioned a blast shield 68 is mounted, the inner edge of the shield being positioned in a groove 69 and the outer edge, which is provided with an enlarged section 70 is positioned in a groove 71 in the rim 11.

In the section shown in Fig. 9 the wire mesh screen or panel 72 which is positioned in the opening 36 of the wheel is mounted in a frame having an inner section 73 positioned in a groove 74 of the hub 10 and an outer section 75 positioned in a groove 76 of the rim 11, the groove 76 also extending in the inner surfaces of the arms 32 and 34.

In the section shown in Fig. 6 the blast shield 77, mounted in a channel-shaped frame 78 is positioned in the groove 79 of a rim 80 similar to the rim 11 and in this section an opening 20 for the locking pin 19 is shown. The locking pin 19, which is adapted to extend through the inner wall 46 is mounted in a housing 81 and resiliently urged inwardly by a spring 82 positioned against the inner end of the housing and also against a collar 83 mounted on the pin. The pin is 75

adapted to be withdrawn by energizing electro magnetic elements 84 and 85 which are connected in the circuit of the device by wires 86 and 87.

The contact 84 extends through a slot 88 in the housing 81 and the inner end of the contact is secured to the pin 19 by brazing, welding, or the like. The housing 81 is secured to the wall 46 with fastening elements such as the screws 89.

The cores 30 and 31 of the cleaning brushes 21 and 22 are mounted on rods 90 and 91, the inner ends of which are secured in openings 92 and 93 of the discs 49 and 50 and the outer ends on the shaft 27 upon which the pinions 23 and beveled gears 25 and 26 are mounted. The shaft 27 is rotatably mounted in arms 94 and 95 of a bracket having a base 96 and the base 96 is secured to a side wall 97 by screws (or the like as indicated by the numeral 98). The idler 24 is mounted on a shaft 99, the ends of which are also mounted in the arms 94 and 95 of the bracket.

By this means the cleaning brushes are mounted in the housing with the inner ends rotated by the shaft 39 at the center of the wheel or circular sash and as the panels, and particularly the glass panels pass between the brushes as illustrated in Fig. 10, the panels are cleaned making it possible to clean a window by starting the motor 14 and rotating the wheel or sash so that the panel or section to be cleaned passes through the brushes.

With the parts designed and assembled as illustrated and described a circuit may be completed to the motor 14 with the motor connected by a wire 100 to an electric light cord plug 101 and with the opposite side of the circuit completed by a wire 102 through contacts 103 and 104 of a switch to the opposite side of the plug, the wire 102 being connected to the contacts 84 and 85 and from the contact 85 to the contact 104 with a wire 105 and from the opposite contact of the switch to the plug 101 by a wire 106. The switch is also provided with a contact 107 that completes a circuit back to the motor.

The circuit is also provided with an element, such as a selenium cell or photoelectric tube 108 which is connected by a wire 109 to the wire 106 and by a wire 110 to the wire 105. With the circuits connected in this manner a flash of light influencing the elements 108 draws the contacts 84 and 85 together, withdrawing the blocking pin 19 whereby the motor 14 is actuated to move the protecting shield 68 across the opening and with the arm of the switch actuated to connect the terminals 103 and 104 a circuit may also be completed to the motor with the circuit withdrawing the pin 19 to permit rotation of the wheel. Also with the arm 111 of the switch positioned to engage the contact 107 a circuit may be completed directly to the motor to rotate the wheel to position either the glass or screen over the opening or between the openings 47 and 50.

In the design illustrated in Fig. 13 the circular sash or wheel 112, which is provided with a hub 113 includes a rim 114 having teeth 115 on the outer surface and arms 116 and 117 which connect the rim to the hub. By this means the wheel is divided into two sections providing segments 118 and 119, the segment 118 being provided with glass panels 120 and the segment 119 being provided with a shield 121 of heavy material, suitable for withstanding a blast such as an explosion of an atomic bomb or the like.

The wheel or sash of this design is positioned in a housing having a base 122, and walls 123 and 124 and an upper panel 125. The wheel is mounted between front and rear panels and cleaning brushes 126, similar to the brushes 21 and 22 extend between the gear assembly 127 on the bracket 128 and the hub 113 of the wheel, the brushes being mounted on rods 129, similar to the rods 90 and 91.

It will be understood, therefore, that the circular sash or wheel may be provided with two, three, or any suitable number of segments whereby the openings through the

window frame may be sealed with a panel of solid material, such as indicated by the numeral 68 in Fig. 8 or with glass as indicated by the panels 62 and 63, or with a wire screen such as the screen 72.

The wheel may also be rotated by pressing a button to clean the glass or other material and with the button or switch 111 located in a control room or tower windows of a building may be opened, sealed, or cleaned as may be desired.

The motor 14 may be replaced by other power means and the brushes 21 and 22 may be replaced with cleaning elements of different types and designs. It will also be understood that a lock of any other type or design may be provided and other means may be used for applying and withdrawing the lock.

The rim of the wheel and also the pinions having the rounded teeth may be made of plastic, such as rubber, or other suitable material.

It will be understood that other modifications, within the scope of the appended claims, may be made in the design and arrangement of the parts without departing from the spirit of the invention.

What is claimed is:

1. In a circular window, the combination which comprises a rectangular-shaped window housing having a base, end walls, an upper panel, a rear wall, a front panel and a horizontally disposed rail at the lower edge of the front panel, a shaft mounted on the rear wall at the back of the window and on the horizontally disposed rail at the front, a wheel having a hub through which the shaft extends, a rim supported from the hub by a web, the web having segmental openings therethrough, a transparent panel in one of the segmental openings of the wheel, and means for rotating the wheel.

2. In a circular window, the combination which comprises a rectangular-shaped window housing having a base, end walls, a rear wall, an upper panel providing a cover, an upper panel providing a front wall and a horizontal disposed rail at the lower edge of the upper panel at the front, a shaft mounted on the rear wall at the back of the

35
40

window housing and on the horizontally disposed rail at the front, a wheel having a hub through which the shaft extends and a rim supported from the hub by a web and said web having segmental openings therethrough, a

5 transparent panel in one of the segmental openings of the wheel, a screen in one of the segmental openings of the wheel, a continuous gear rack on the peripheral surface of the rim of the wheel providing a gear, a pinion rotatably mounted in the housing and positioned in meshing relation with the gear, a motor and means operatively connecting the motor to the pinion.

3. In a circular window, the combination which comprises a rectangular-shaped window housing having a base, end walls, a rear wall, an upper panel providing a cover,

15 an upper panel providing a front wall and a horizontal disposed rail at the lower edge of the upper panel at the front, a shaft mounted on the rear wall at the back of the window housing and on the horizontally disposed rail at the front, a wheel having a hub through which the shaft extends, a 20 shaft extends and a rim supported from the hub by a web and said web having segmental openings therethrough, a transparent panel in one of the segmental openings of the wheel, a screen in one of the segmental openings of the wheel, a continuous gear rack on the peripheral surface 25 of the rim of the wheel providing a gear, a pinion rotatably mounted in the housing and positioned in meshing relation with the gear, a motor, means operatively connecting the motor to the pinion, roller bearings in the hub of the wheel rotatably mounting the wheel on the shaft, wipers mounted at the sides of the wheel for cleaning parts thereof as the wheel is rotated, and latching means for locking the wheel in adjusted positions.
